CLAIM

The ornamental design for a cross-shaped display stand, as shown and described.

DESCRIPTION

FIG. 1 is a top front perspective view of an embodiment of a cross-shaped display stand in accordance with the present invention;

FIG. 2 is a bottom rear perspective view thereof;

FIG. 3 is a front view thereof;

FIG. 4 is a rear view thereof;

FIG. 5 is a right side view thereof, with the left side view being a mirror image;

FIG. 6 is a top view thereof;

FIG. 7 is a bottom view thereof;

FIG. 8 is a top front perspective view of another embodiment of a cross-shaped display stand in accordance with the present invention;

FIG. 9 is a bottom rear perspective view thereof;

FIG. 10 is a front view thereof;

FIG. 11 is a rear view thereof;

FIG. 12 is a right side view thereof, with the left side view being a mirror image;

FIG. 13 is a top view thereof; and,

FIG. 14 is a bottom view thereof.

The dot-dash broken lines in FIGS. 1-14 represent the boundary between claimed and non-claimed subject matter. The dash-dash broken lines depict portions of the article that form no part of the claimed design.
